mesne assignments, to American Optical Com-
pany, Southbridge, Mass., a voluntary associa-
tion

Application April 21, 1944, Serial No. 532,087

7 Claims. (Cl. 51—65)

1

This invention relates to honing or sharpening machines and has particular reference to apparatus for sharpening blades for microtomes or the like.

This invention relates to apparatus of the type set forth in the application of Albin A. Gradisar, filed August 14, 1942, Serial No. 454,867, issued as Patent Number 2,402,155, dated June 18, 1946, and to new and improved features for an apparatus of the type set forth in that application.

An object of the invention is to provide a new and improved damping mechanism for the blade operating means which will provide better control and which will operate independent of the operating pressure.

Another object of the invention is to provide new and improved means whereby the pressure of the blade on the sharpening member may be controlled independent of the damping mechanism.

Another object of the invention is to provide new and improved means for automatically stopping the sharpening action.

Another object of the invention is to provide a new and improved mechanism for stopping the sharpening operation which comprises a hydraulic valve which is controlled electrically.

Another object of the invention is to provide new and improved means for stopping the blade operating apparatus with the blade raised from the sharpening member.

Other objects and advantages of the invention will become apparent from the following description taken in connection with the accompanying drawings. It will be understood that many changes may be made in the details of construction and arrangement of parts without departing from the spirit of the invention as expressed in the accompanying claims. I, therefore, do not wish to be limited to the exact details of construction and arrangement of parts shown and described as the preferred form has been shown by way of illustration only.

Referring to the drawings:

Fig. 1 is a side view, partially in section, of an apparatus embodying the invention;

Fig. 2 is a top or plan view thereof;

Fig. 3 is a sectional view taken on line 3—3 of Fig. 2 looking in the direction of the arrows;

Fig. 4 is a sectional view taken on line 4—4 of Fig. 3 looking in the direction of the arrows;

Fig. 5 is a diagrammatic illustration showing the positions assumed by the blade;

Fig. 6 is a sectional view taken on line 6—6 of Fig. 2 looking in the direction of the arrows;

2

Fig. 7 is a sectional view taken on line 7—7 of Fig. 6 looking in the direction of the arrows;

Fig. 8 is a sectional view taken on line 8—8 of Fig. 2 looking in the direction of the arrows;

Fig. 9 is a sectional view taken on line 9—9 of Fig. 8 looking in the direction of the arrows;

Fig. 10 is a sectional view taken on line 10—10 of Fig. 4 looking in the direction of the arrows;

Fig. 11 is a sectional view taken on line 11—11 of Fig. 10 looking in the direction of the arrows;

Fig. 12 is a sectional view taken on line 12—12 of Fig. 10 looking in the direction of the arrows;

Fig. 13 is a diagrammatic view of the hydraulic system for operating the apparatus;

Fig. 14 is a top view of the mechanism for stopping the blade in raised position; and

Fig. 15 is a sectional view taken on line 15—15 of Fig. 14 looking in the direction of the arrows.

The apparatus shown comprises a hydraulic source 1 for containing a supply of a fluid 2. Adjacent the member 1 is the support 3 which may be a table, bench or other form of support which is supported by the upright members 4 and on the support 3 is positioned the frame or the like 5.

The motor 6 is provided for driving the pump 7 to provide power to the hydraulic system.

The frame or support 5 is provided with the marginal tracks or guideways 9 and 10 adjacent the opposite longitudinal edges thereof and in these tracks 9 and 10 are positioned the rollers 11 which are movable on said tracks to thereby move the carriage 12. The carriage 12 is adapted to be moved longitudinally on the rollers 11 as previously described and is motivated by means of the hydraulic cylinder 13 containing a piston.

The carriage 12 is provided with adjusting screws 14 adjacent the opposite ends thereof for supporting the sharpening or honing plate support 15 which carries the honing or sharpening plate member 16. It will be noticed that at one end the member 15 is supported by one adjusting screw 14 whereas the opposite end is supported by a pair of such screws 14.

Adjacent the opposite ends of the plate 16 are provided the lubricant reservoirs 17 and 18. These reservoirs are filled with a lubricating solution such as a solution of water and glycerine with the solution comprising approximately 10% glycerine and a rust inhibitor.

It will be noted that these reservoirs are provided with the inclined faces 19 and 20 respectively. These inclined faces 19 and 20 are provided to allow the lubricant to flow on to the surface of the plate 16 at the end of each stroke.

Because of these inclined faces a greater lubrication is obtained.

From the pump 1 the fluid from the hydraulic tank 1 flows through the pipe 21 to the flow valve 22 and to the pressure regulating valve 23. From the pressure regulating valve the fluid flows to the pressure gauge 24 and reverse valve 25 from which it flows to the blade oscillating valve 26 which serves to oscillate the blade 27 and applies the necessary pressure upon said blade as hereinafter described.

When the blade has been oscillated the fluid flows through the flow regulation valve 22 and pipe 27a to the reverse valve 28 which is attached to the blade oscillator 26 from which it flows to one end of the piston 13 to operate the carriage as previously described.

The pipe 29 connects the exhaust end of the piston to the reverse valve 28 from which the exhaust pipe 30 returns the flow to the tank 1.

The blade oscillating mechanism 26 consists of the chamber 31 containing the rotor or vane 32 (see Figs. 8 and 9). The pipes 33 and 34 which are connected with the chamber 31 act alternatively as exhaust and pressure lines. The needle valves 35 and 36 are provided to dampen the contact of the blade with the surface of the plate 16. These valves 35 and 36 are adjustable to adjust the exhaust flow to the lines 33 or 34 from the chamber 31.

In the chamber 31 is provided the head 37. When the rotor 32 is in the position shown in Fig. 9 the line 33 will serve as a flow or pressure line to supply fluid to the chamber and the line 34 will serve as an exhaust line to exhaust the fluid from the chamber. When the rotor 32 is in reverse position then the line 34 will serve as a flow or pressure line and the line 33 as an exhaust line. With the valves 35 and 36 the rate of exhaust can be actually controlled to regulate the damping mechanism of the blade on the plate 16. The exhaust pipe 38 is provided to return to the tank 1 any hydraulic fluid which may escape from the chamber 31. The channel 39 is provided surrounding the rotor shaft 40 to receive this escaping fluid and conduct it to the pipe 38.

The main control 41 is connected into both the circulating system for the hydraulic pressure and also the main electric circuit so as to enable the operator to simultaneously control both and thus stop and start the entire machine. This main control 41 includes a main control handle 47 which operates both a valve 46 controlling the hydraulic pressure and a switch 51 for opening the main line electric current. The main control handle 47 is ordinarily operated automatically to stop the running of the machine and is operated manually to restart the operation of the machine. The valve 46, as shown in Fig. 13, is in the exhaust line 42 from the reverse valve 25; and when the valve 46 is closed by movement to the dotted line position shown in Fig. 13, further operation of the rotor 32 and the hydraulic cylinder 13 is stopped. The handle 47 is moved manually against the action of the spiral spring 48 to close the main electric circuit and to open the hydraulic line 42 to the exhaust; and is retained in this position against the action of the spring 48 by an armature controlled latch 44. This latch 44 is not only electrically operated by its armature to release the handle 47 but may also be operated manually by the emergency push button 45 to release the handle 47.

For automatically timing the running cycle of the machine the automatic timing device or clock 75

49 is provided. The time controlled circuit closing device 49 comprises a conventional clock mechanism having a manually set switch arm 49. As shown, the switch arm 49A is interposed in the 5 electric circuit between the intermittently operated, normally open switch 50 associated with the blade oscillating valve 26 and the main controlling means 41 for the normally closed switch 51. This timing device 49 is connected in series (see Fig. 13) with the microswitch 50 (which switch as explained below is closed during only one period of the cycle of operation of the machine) and with the solenoid 43 which operates the armature 44 and releases the handle 47 energized by the spring 48. This simultaneously closes the valve 46 and opens the switch 51 (see Fig. 13). The main line circuit supplies current to an electrical motor 53 provided with the usual choke coil 52.

The arrangement for oscillating or reciprocating the blade in a direction perpendicular to the direction of movement of the plate 16 comprises the motor 53 which rotates the fly wheel 54 and pinion 55 which drives the gear 56 which drives the pitman 57 through the crank bearing 58. As 20 illustrated by Fig. 12 of the drawings the crank which is journaled in the pitman 57 is slightly offset with respect to the bearing 58 and therefore as the crank is rotated by the gear 56, the pitman 57 is caused to oscillate due to the movement of the crank. The member 59 is fastened to the oscillating shaft 60 by the set screw 61 and thereby oscillation of the oscillator 57 causes reciprocation of the shaft 60 and blade.

The blade 27 is supported by the retainer 62. 35 The key 63 and screw 64 engage openings in opposite ends of the blade 27 to retain the blade in operative position relative to the holder 62.

The holder 62 is provided with the shaft 65 which extends through an opening in the shaft 66 40 and is held therein by means of the screw 67 which is threaded into the threaded portion in the shaft 65. The shaft 66 and oscillating shaft 60 are each formed at their engaging ends with suitable clutch faces to effect driving connection therebetween. The pin 68 on the support 62 fits into the hole 69 in the shaft 66 and allows only enough movement for the blade to firmly engage the plate 16.

In Figs. 14 and 15 is shown the mechanism for 50 permitting stopping of the blade movement only when the blade is raised from the sharpening member 16. This comprises the rotatable rim 70 having the cam 71 thereon adapted to engage the cam roller or rider 72 which is retained in position by the spring 73. The roller or rider 72 is mounted on the arm 74 of the microswitch and the pin 75 is provided beneath the arm 74 to operate said microswitch. The roller 72 and cam 71 are in engagement only on the upstroke of the cam thereby preventing the stopping of the machine with the blade in contact with the sharpening member.

From the foregoing it will be seen that I have provided simple, efficient and economical means and advantages of the invention.

Having described my invention, I claim:

1. In a device of the character described, a sharpener member, a blade holder, mechanism operated by fluid pressure for effecting relative movement between the sharpener member and blade holder in one direction, independent electrically operated mechanism for effecting relative movement between the sharpener member and blade holder in a different direction, and a common control member having starting and

stopping positions associated with the two mechanisms for stopping and starting both said mechanisms, said control member being biased toward its stop position.

2. In a device of the character described, the combination as set forth in claim 1 including a releasable trip for maintaining the control member in its start position.

3. In a device of the character described, a sharpening member, a blade holder, means including a fluid operated servo-motor for oscillating said blade holder relative to said sharpening member to bring the opposite sides of the blade into operative relation therewith, means comprising a cooperating piston and cylinder for effecting relative reciprocatory movement between the sharpening member and the blade holder, and a separate control valve actuated by the oscillation of said blade holder for reversing the direction of movement of the piston in the cylinder therefor.

4. In a device of the character described, in combination with a sharpener plate, mechanism for oscillating a blade from one operative position relative to said sharpener plate to another operative position including an oscillating member mounted to extend transversely of the plate, a blade holder pivoted to said oscillating member on an axis substantially passing through the blade and normal to the axis of the oscillating member to permit the blade to accommodate itself to the surface of the sharpener plate on successive oscillations of the member, and a stop means extending between and cooperating with the member and blade holder for limiting the pivotal movement of the blade holder relative to the oscillating member and plate.

5. In a device of the character described, an elongated sharpening plate mounted on a bed for endwise reciprocation relative to the bed, motor operated means for reciprocating said plate, a support extending transversely over said plate and mounted on said bed, a blade holder mounted on the support for oscillatory and reciprocatory movement, means for oscillating the blade holder for alternately presenting opposite sides of a blade to the sharpening plate, and a variable speed mechanism including a motor operated pitman connected to the blade holder for positively reciprocating the blade holder lengthwise of the support and transversely of the sharpening plate independently of the means for oscillating the blade holder so that a blade carried by the blade holder may be caused to selectively traverse the same or different surface areas of the plate on repeated reciprocations thereof.

6. In a device of the character described comprising a sharpener member and an associated

blade holder, power driven mechanism for imparting relative movement between the sharpener member and blade holder for sharpening a blade on said member, an oscillatory blade flipping means connected to said blade holder for swinging opposite sides of a blade alternately into and out of contact with said sharpener member, power control means connected to the power driven mechanism and to the blade flipping means and movable in opposition to a resilient pressure to an operative position for initiating the supply of power to said mechanism and said flipping means, releasable holding means for maintaining said power control means in said operative position, and a power stop controller connected to said holding means and to said flipping means at a position thereon so as to automatically release said power control means to interrupt the supply of power and stop the blade holder with the blade out of contact with said sharpener member.

7. The structure recited in claim 6 wherein said power stop controller includes clockwork operating means which becomes automatically effective after a predetermined operating period for allowing said power stop controller to interrupt said supply of power and stop said blade holder with the blade out of contact with said sharpener member.
